DES. 1952

George Wilkinson, of Providence, R.I.
Assignor to

Yorkham and Company, of the same place.

Letters Patent No. 1952-Dated June 7th 1864.

Design for a Spoon or Fork Handle.

The schedule referred to in these Letters Patent and making part of the same.

To all whom it may concern:

Be it known that I, George Wilkinson, of Providence, in the County of Providence and State of Rhode Island, have invented or produced a new and original design for a handle for spoons, forks, and other articles of table ware; and I do hereby declare that the following is a full and exact description of the same, reference being had to the accompanying drawings making part of this specification, in which-

Fig. 1. is a plan of the upper surface of the design, and

Fig. 2. is a lateral view of the same.

In the said drawings a. a. is the shaft or longitudinal feature of the handle, the outline of which increases in width gradually from the bowl to the top or extremity which terminates in an abrupt curve e. e. This curve is surmounted and partially concealed, by the ornamental scroll & raff work A., beneath which is situated a round medallion B. which is incorporated with the shaft a. at a distance from the curved extremity thereof. the shaft and medallion B. being distinct features which are combined and incorporated to produce a highly ornamental effect.

DES. 1952

2 This is an oval roselet banded on the shaft or stem at the lower portion of which terminates in a bushel through the medium of which the shaft is united and imperceptably merged into the bowl of a spoon or ladle or the blade of a fork or knife.

What I claim and desire to secure by Letters Patent is—

Substantially the above specified design for a handle for spoons, forks, and tableware, as represented.
